WINDOW LOCK

Charles J. Rateike, Chicago, Ill.

Application July 20, 1932, Serial No. 623,529

10 Claims. (Cl. 292—210)

This invention relates to window locks and more particularly to an adjustable lock for windows, although certain features thereof may be employed with equal advantage for other purposes.

It contemplates more especially the provision of an improved lock that is compact, adjustable, inexpensive, and capable of substantially concealed installation without entailing much labor or expense.

Numerous types of window locks have heretofore been proposed but these have not proven entirely satisfactory owing to the fact that they are very obtrusively attached, and are rather cumbersome in their operation and installation. Then, too, window locks of the character mentioned have not been capable of varied adjustment to afford complete window utility for locking and ventilation purposes.

One object of the present invention is to simplify the construction and improve the operation of devices of the character mentioned.

Another object is to provide an improved locking expedient for windows that enables resort to weather stripping as a cooperating element.

Still another object is to provide a window lock designed for cooperation with weather stripping to enable the varied engagement for locking and ventilation purposes.

A further object is to provide a lock that has a plurality of adjustments to enable positive locking, uni-directional movement of the window and freedom of movement in both directions without inconvenience or entailing much time of the attendant.

A still further object is to provide a simple and improved window lock that is compact and readily installed without substantial display.

Still a further object is to provide a simple and improved lock that is readily installed in position for cooperation with a weather stripping to accomplish the intended purpose thereof.

Other objects and advantages will appear from the following description of an illustrative embodiment of the present invention.

In the drawings:

Figure 1 is a front view in elevation of a window showing the installed locks of the type embodying features of the present invention.

Figure 2 is a fragmentary sectional view taken substantially along line II—II of Figure 1.

Figure 3 is an enlarged fragmentary view showing a lock installed in position on the upper window frame.

Figure 4 is a similar view showing the lock

embodiment features of the present invention installed upon a lower window frame.

Figure 5 is a perspective view of a serrated bar member utilized for cooperation with the lock disclosed in Figures 3 and 4.

Figure 6 is an enlarged fragmentary view of weather stripping provided with an irregular protruding edge for cooperation with the window lock.

Figure 7 is a top view of the weather stripping disclosed in Figure 6, there being shown a strip reinforcement for the irregular protruding ridge or edge.

Figure 8 is a sectional view taken longitudinally through the lock disclosed in Figure 3.

Figure 9 is an end view of the lock disclosed in Figure 8.

Figure 10 is a front view of the lock with the outer face plate removed to clarify the showing.

Figure 11 is a perspective view of the adjusting lever disclosed in operative position in Figures 8 and 10.

Figure 12 is a perspective view of the locking plate constituting an element of the lock assembly disclosed in Figure 10.

Figure 13 is a front view of a lever strip disclosed in assembled position in Figure 10.

Figure 14 is a side view showing the assembled casing disclosed in Figure 9.

The structure selected for illustration comprises a window frame 10 of standard or approved construction with stiles 11 thereof properly grooved for receiving the customary lower and upper window sashes 12 and 13, respectively.

The window sashes 12 and 13 are normally maintained within the stiles 11 for slidable displacement owing to the guide members 14 which are in projected attachment to the stiles 11. As shown, the window sashes 12 and 13 are provided with transparent window panes 15 and 16, respectively, to serve as a closure therefor in accordance with modern and standard practice.

In order to provide proper ventilation and yet afford burglary protection against admission through the window frame 10, locks are provided on each of the sashes 12 and 13 along a side member thereof. The locks comprise, in this instance, complementary case sections 17 and 18 which form an enclosure in their assembled position. The case sections 17 are stamped or otherwise shaped from sheet material to provide upstanding side flanges 19 and an end flange 20 along three sides thereof with the open end providing an extension 21 which is substantially a

60

105

110

complement to the upstanding flange 20. As shown, the side flanges 19 have extensions 22 terminating just short of the extension 21 and spaced upwardly therefrom to provide a cut-out 23 which affords cooperation with the complementary top plate 18 as will more presently appear.

The top plate 18 is somewhat wider than the bottom casing section 17 to provide overlapping regions 24 having apertures for the reception of fasteners such as screws 25 therethrough. The screws 25 cooperate with the window sash to effect the attachment of the lock casing in a correspondingly shaped cavity provided therein. The top plate 18 has a depending flange 26 sized for disposition between the bottom casing extensions 22 to occupy the open end thereof just above the bottom extension 21, there being side flanges 27 extending from the depending flange 26 to occupy the cut-outs 23 provided in the bottom casing section 17. An upwardly extending projection or ridge 28 is provided intermediate the rear flange 20 to cooperate with a correspondingly shaped slot 29 provided in the top plate 18. In consequence thereof, the ridge 29 may be swaged or flattened to effect the permanent assembly and attachment of the top section 18 to the bottom sections 17, and the side extensions 22 of the former may be or are preferably turned over to engage the depending top section flange 26 to provide added complementary connection between the casing sections.

The interior mechanism of the case sections 17 and 18 comprise, in this instance, a locking rod 30 which has a reduced extremity 31 projecting through an aperture provided in the end flange 20, the reduced extremity 31 being swaged to provide an enlarged head 32 for precluding the removal of the locking rod 30 and permitting its free pivotal displacement in locking and unlocking positions. A positioning plate 33 is provided beneath the locking rod 30, it being substantially rectangular and provided with a rolled edge defining a tubular cylindric barrel 34 with an end thereof closed by an upstanding flange 35 pressed or otherwise shaped from the plate 33. An aperture 36 is provided in a corner of the plate 33 for pivotal engagement with a stud 37 anchored in the bottom section 17 so that the side edge 38 proximate to the aperture 36 may be disposed adjacent and in alignment with the end flange 20 of the bottom section 17. A coiled spring 39 is disposed within the tubular barrel 34 for contact with the bottom section flange 20 so as to urge the plate 33 to its extreme clockwise position (viewed from Figure 8) with the flange 35 abutting against the locking rod 30 which is correspondingly moved in a similar locking direction.

A locking lever 40 is pivoted about a shank 41 to a pin 42 provided through the casing sections 17 and 18, the pin 42 being held in position by a fastener such as a nut 43. So that the lever 40 may not be accidentally moved or rotated, it is provided with an ear 44 spaced from the shank 41 and connected therewith through the medium of a rectangular cam 45. The lever shank 41 and ear 44 are provided with aligned apertures 46 for the projection of the shank 42 therethrough. The pin 42 has a coiled spring 47 in enveloping relation therewith between the ear 41 and ear 44, thereby imparting a frictional reaction thereto for avoiding accidental pivotal movement of the lever 40. The lever 40 has an upwardly off-set extension 48 which projects through an arcuate slot 49 provided in the top plate 18 so as to be exteriorly accessible for ro-

tating the lever 40 within the limit of the slot 49. The rectangularly shaped projection 45 constituting a part of the lever shank 41 abuts against the locking rod 30. In consequence thereof, the lever 40 may be utilized to pivot the locking rod 30 to its extreme open and closed position with an intermediate neutral point enabling the closing of the window, but precluding the opening thereof. It will be observed that the locking rod 30 in its pivotal movement will effect corresponding translation of the positioning plate 33 which has an arcuate slot 50 provided therethrough so as to accommodate the pin 42 which is stationary relative to the movement of the plate 33 and afford the movement of the latter.

Should it be desired to positively hold the lever in adjusted positions, a detent lever 51 is pivoted to the side flange 19 as at 52, it having depending projections 53 for the reception of a coiled spring 54 thereon to normally urge the detent to its extreme clockwise position (viewed from Figure 13). An arcuate lug 55 is formed on the top edge of the detent 51 to project through a slot 56 provided in the top plate member 18 intermediate the extremities of the arcuate slot 49 provided thereon. Consequently, the lever 40 cannot be moved past the projecting detent 56 to change the setting of the lock unless the detent 56 is depressed by the attendant.

The different positions of the locking lever 40 determines the movement of the locking rod 30 which rides in an inclined slot 57 provided in the depending flange 26 of the top casing section 18, the locking rod 13 projecting therethrough to engage a serrated bar of weather stripping provided on the window stile in a manner which will appear more fully hereinafter.

It will thus be apparent that the movement of the locking rod 30 to its extreme clockwise position (viewed from Figure 8) responsive to the spring urged plate 33, will cause the extremity thereof to approach the bottom casing section 17 owing to the guidance offered by the inclined slot 57. A bar 58 having a plurality of interrupted serrations 59 thereon is fixed to project from the stiles 11 in the path of the locking rod 30. The bar 58 is provided with apertures 60 to receive fasteners therethrough for attachment to the stiles 11 in a position so as to be in the path of the casing section 18 defined by the bottom extension 21 thereof and the side flange extensions 22 (Figure 9). In consequence thereof, a locking rod 30 when in its extreme clockwise position will register between the serrations 59 provided on the bar 58 so as to preclude movement in either direction. The serrations 59 have inclined sides 61 which enable the rod 30 to recede therefrom when the lever 40 is positioned to afford the receding motion thereof, thereby enabling the elevation of the lower window sash 12. It is of utmost importance to note that the bar 58 may be dispensed with in lieu of weather stripping 62 which has the sash projecting ridge 63 thereof provided with lateral depressions 64 shaped to correspond with the serrations 59 provided on the bar 58. So that the depression 64 may be permanent and reinforced, a weather strip reinforcement plate 65 is disposed within the weather strip ridge 63. Consequently, the weather strip ridge 63 is reinforced and the depressions 64 provided therein to correspond with the top initially formed in the reinforcement strip 65 to make the structure rigid.

The locking rod 30 cooperates, therefore, with the weather strip 62 and the windows may be low-

- ered or raised to provide ventilation without enabling any access therethrough. In the upper window sash 13, the top plate 18 has the slot 57 in the depending flange 26 thereof, inclined in an opposite direction to that shown in Figure 9, and in all other respects the construction of the window locks are identical with the lever 40 operating on the other side of the locking member 30.
- 10 The operation of the lock mechanism may be understood by considering separately each of its three different settings. These are, first, the unlocked position; second, the locked setting; and third, the intermediate setting which permits the window to close but does not permit its further opening. Considering the control lever 48 set at that end of the arcuate slot 49 which is marked "0" (full line position shown in Figures 3 and 4), the elements of the lock (for the lower sash—Figure 4) are then arranged as shown in Figure 10. The elements of the lock for the upper sash would be arranged similarly except in an oppositely relative direction to a transverse axis. In this position, the locking rod 30 is positioned at the extremity of the slot 57 as indicated in dotted outline in Figure 9, and thereupon is held clear and free of the ratchet or serrated projections 59 of the bar 58 or depressions 64 of the weather stripping 62 so that the relative motion between locking rod 30 and ratchet does not result in interfering contact; consequently, the window is not prevented by the locking device from being opened or closed. The locking rod 30 is definitely held in this position, and its motion in one direction is prevented by the end of the inclined slot 57 while its motion in the other direction is prevented by the corner contact of the lever projection 45 as clearly shown in Figure 10, so that it is held substantially in the position indicated and will not interfere with the rack or ratchet teeth 59 or 64.
- 40 Secondly, considering the control lever 48 set at the other end of the arcuate slot 49 marked "L" and represented by the dotted outline in Figure 4, the parts are then arranged as shown by the full line outline in Figure 8. An attempt to move the window 12 upward will cause the locking rod 30 to bind against the lower edge of the tooth 59 of the bar 58. The extremity of the slot 57 will prevent the movement of the locking rod 30 away from its fixed position so that the reaction of the ratchet teeth 59 upon the locking rod 30 will prevent an upward movement of the window sash 12. An attempt to lower the window 12 will result in a force reaction between the upper part of ratchet teeth 59 and the locking rod 30 which further exerts force against the inclined edge of the slot 57 and the projecting flange 33' of the positioning plate 33, this being exerted through the medium of the lever 40. The plate 33 is prevented from yielding to this force and turning about its pivot 37 owing to the spring 39, and thus the plate 33 is held in fixed position and so holds the locking pin 30 in the lower extremity of the slot 57. The force between the ratchet teeth 59 and the locking pin 30 is transmitted by means of the lock sections 17—18 to the sash 12, thereby preventing the window from moving downward. The sash 12 cannot, therefore, move relatively to the window frame 10 and the former is held against any possible opening or closing.
- 75 Thirdly, considering the control lever 40 set at the intermediate position shown in dotted outline in Figure 4, the parts of the lock with the exception of the cam 45 will be arranged as represented in full outline in Figure 8. The cam 45 will be in the position represented by the dotted outline, and should any attempts be made to raise the window, the locking pin 30 will bind against the lower edge of the ratchet teeth 59. The lower end of the slot 57 will hold the locking pin 30, and thus the force reaction between the ratchet teeth 59 and pin 30 is transmitted by means of the lock sections 17—18 to the sash 12 and the window cannot be raised. However, force is exerted to lower the window 12 and the upper edge of ratchet teeth 59 exerts force against the pin 30, this causing the latter to exert force against the edge of the projection 35 of the plate 33, this overcoming the urge of the spring 39 to revolve the plate 33 about its pivot 37 until the positions of pin 30 and plate 33 (Figure 10) have been reached or approached as the sash 12 moves down and the locking rod 30 moves over the ratchet tooth 59 as it assumes a position in the slot 57 at or approaching that shown in dotted outline in Figure 9. Thus the locking rod 30 glides over the tops of the ratchet teeth 59 to allow closing, but precluding further opening of the window 12. The upper sash 13 operates similarly, but the lock elements function and are positioned opposite to the lock mechanisms of the lower sash 12.
- Various changes may be made in the embodiment of the invention without departing from or sacrificing any of the advantages as defined in the appended claims.
- I claim:
1. In a device of the character described, the combination with a window frame having sash guiding stiles, of window sashes in said stiles, weather stripping attached to said stiles, a lock mechanism fixed to said window sashes for cooperation with said weather stripping, and adjustable means for controlling said lock mechanism to selectively lock said sashes against movement.
  2. In a device of the character described, the combination with a window frame having sash guiding stiles, of window sashes in said stiles, weather stripping attached to said stiles, a lock mechanism fixed to said window sashes for cooperation with said weather stripping, adjustable means for controlling said lock mechanism to selectively lock said sashes against movement, and a cam operatively connected to said adjustable means for varied positioning responsive thereto to render said sashes immovable, movable in either direction, or only movable toward the closing position thereof.
  3. In a device of the character described, the combination with a window frame having sash guiding stiles, of window sashes in said stiles, weather stripping attached to said stiles, a lock mechanism fixed to said window sashes, said locking mechanism including a translatable locking pin for cooperation with said weather stripping, and an adjustable camming device operatively engaging said locking pin to selectively lock said sashes against movement, said camming device having varied adjustment to render said sashes immovable, movable in either direction, or only movable toward the closing position thereof.
  4. In a device of the character described, the combination with a window frame having sash guiding stiles, of window sashes in said stiles, lock mechanism fixed to said sashes, means fixed to said stiles for cooperation with said lock mechanisms, and adjustable means for controlling said

- lock mechanism to selectively lock said sashes against movement.
5. In a device of the character described, the combination with a window frame having sash 5 guiding stiles, of window sashes in said stiles, lock mechanism fixed to said sashes, and means fixed to said stiles for cooperation with said lock mechanisms, said locking mechanism including a translatable locking pin for cooperation with 10 said stile attached means, and an adjustable camming device operatively engaging said locking pin to selectively lock said sashes against movement, said camming device having varied adjustment to render said sashes immovable, movable in either direction, or only movable toward the closing position thereof.
6. In a lock, the combination with a casing, of a locking pin movably connected to said casing to project through an end wall thereof, a plate pivoted to said casing, means on said plate projecting in the path of said locking pin, spring means for urging said plate to an extreme position, and camming means for adjusting the position of said locking pin for the purpose set forth.
25. 7. In a lock, the combination with a casing, of a locking pin movably connected to said casing to project through an end wall thereof, a plate pivoted to said casing, means on said plate projecting in the path of said locking pin, spring 30 means for urging said plate to an extreme position, and camming means intermediate a plate shoulder and said locking pin for adjusting the position of said locking pin for the purpose set forth.
35. 8. In a lock, the combination with a casing, of a locking pin movably connected to said casing to project through an end wall thereof, there being an inclined slot in the end of said casing to guide the movement of said locking pin in and out of 40 operative position, a plate pivoted to said cas-
- ing, means on said plate projecting in the path of said locking pin, spring means for urging said plate to an extreme position, and camming means intermediate a plate shoulder and said locking pin for adjusting the position of said locking pin for the purpose set forth. 80
9. In a lock, the combination with a casing, of a locking pin movably connected to said casing to project through an end wall thereof, there being an inclined slot in the end of said casing to 85 guide the movement of said locking pin in and out of operative position, a plate pivoted to said casing, means on said plate projecting in the path of said locking pin, spring means for urging said plate to an extreme position, and camming means intermediate a plate shoulder and said locking pin for adjusting the position of said locking pin for the purpose set forth, said camming means having normally related surfaces to hold said plate and/or locking pin against movement in the varied range of adjustment thereof. 90
10. In a lock, the combination with a casing, of a locking pin movably connected to said casing to project through an end wall thereof, there being an inclined slot in the end of said casing 100 to guide the movement of said locking pin in and out of operative position, a plate pivoted to said casing, means on said plate projecting in the path of said locking pin, spring means for urging said plate to an extreme position, camming means 105 intermediate a plate shoulder and said locking pin for adjusting the position of said locking pin for the purpose set forth, said camming means having normally related surfaces to hold said plate and/or locking pin against movement in the varied range of adjustment thereof, and means for maintaining said camming means in adjusted positions. 110
